COMBINED DISPLAY AND DISPENSING STAND FOR MERCHANDISE

Charles Resnick, Freeport, N.Y., assignor to Fred Bronner
Corporation, New York, N.Y.

Filed June 6, 1968, Ser. No. 12,243

Term of patent 14 years

Int. Cl. D6—01

U.S. Cl. D80—9

FIG. 2

FIG. 1 is a front perspective view of a combined display and dispensing stand for merchandise showing my new design; and

FIG. 2 is a rear perspective view thereof.

I claim:

The ornamental design for a combined display and dispensing stand for merchandise, substantially as shown.
